(57) **CLAIM**

The ornamental design for a hub for holding a disc on a cylindrical container, as shown and described.

DESCRIPTION

FIG. 1 is a perspective view of a hub for holding a disc on a cylindrical container showing my new design; the lining of the drawing indicating that the material is substantially transparent.

FIG. 2 is a top plan view of FIG. 1;

FIG. 3 is a front elevation view of FIG. 2;

FIG. 4 is a right side elevation view of FIG. 2;

FIG. 5 is a bottom plan view of FIG. 2;

FIG. 6 is a perspective view similar to FIG. 1 with the lining of the drawing representing a substantially opaque material;

FIG. 7 is a top plan view of FIG. 6;

FIG. 8 is a front elevation view of FIG. 7;

FIG. 9 is a right side elevation view of FIG. 7; and,

FIG. 10 is a bottom plan view of FIG. 7.
